CLAIM

The ornamental design for a baby carrier, as shown and described.

DESCRIPTION

FIG. 1 is a front, top, and right side perspective view of a baby carrier, showing my new design;

FIG. 2 is a rear, bottom and left side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front, top, and right side perspective view of the baby carrier, shown in an alternate state.

The broken lines shown in the drawings illustrate portions of the baby carrier that form no part of the claimed design.

1 Claim, 9 Drawing Sheets
